BRAKE CONTROL FOR COIL WINDING MACHINE

Sven A. Hoffman, Penn Township, Pa., assignor to Allis-Chalmers Manufacturing Company, Milwaukee, Wis.

Application April 10, 1953, Serial No. 347,884

8 Claims. (Cl. 242—4)

This invention relates in general to machines for winding a strand of material upon a ring shaped core and particularly, to an automatic means for varying or controlling the speed of rotation of the shuttle of such a machine whereby the strand being unwound therefrom onto a ring shaped core does not develop any slack. The term "strand" is used broadly herein to include all such things as wire, cord, thread, twine, tape or tubing.

Winding machines for applying strand to ring shaped or annular elements such as cores of transformers, in which a rotary shuttle is interrelated with the loop of the core, have been provided with braking means to control the tension of strand as it is unwound from the shuttle onto the core. However, such braking means as provided in those machines have merely been suggested in such a manner that they provide a constant friction impeding the rotation of the shuttle and are not automatically controlled.

In accordance with this invention the operation of such machines can be improved by making such braking means automatic to tension the strand in accordance with the tendency of the strand to develop slack as it is being unwound from the shuttle onto the core interrelated with the shuttle. That is, during each revolution of the shuttle, the tension of the strand is automatically controlled by varying the action of the braking means.

It is therefore an object of this invention to provide an improved winding machine embodying a rotary shuttle from which strand material such as wire is wound onto a closed annular ring or core interrelated with the rotary shuttle.

Another object of this invention is to provide in a strand winding machine in which the speed of the shuttle is varied with each revolution of the traveling ring of the winding machine, whereby strand supplied from the shuttle to an interrelated member is maintained under tension.

Objects and advantages other than those above set forth will be apparent from the following description when read in connection with the accompanying drawings in which:

Fig. 1 is a side elevation of the winding machine having a rotary shuttle for winding strand, in this instance wire, therefrom onto a ring shaped core that is to be interrelated with the shuttle, made in accordance with the teachings of this invention;

Fig. 2 is a plan view of the machine illustrated in Fig. 1 with a ring shaped core and core holding means shown in position on the winding machine whereby the wire may be wound about that core;

Fig. 3 is an elevation view of the apparatus shown in Fig. 2 taken from the left hand side thereof showing wire being applied to the core;

Fig. 4 is a front elevation view of the apparatus represented in Fig. 2;

Fig. 5 is an enlarged sectional view taken along line V—V of Fig. 1;

2

Fig. 6 is an enlarged elevation view partly in section taken along line VI—VI of Fig. 1;

Fig. 7 is an enlarged elevation view of part of the rotary shuttle and traveling ring taken along line VII—VII of Fig. 1, showing a segmental lock means for the shuttle whereby it may be directly driven by the traveling ring of the machine in order to wind a supply of wire onto the shuttle;

Fig. 8 is an enlarged elevation view of part of the rotary shuttle and traveling ring of the winding machine with the segmental lock means attached thereto. This view is taken from the right side of these members as viewed in Fig. 7;

Fig. 9 is a diagrammatic view of the rotary shuttle and part of the automatic braking means provided for tensioning the wire in accordance with the teaching of this invention, with various parts enlarged. This automatic braking means is shown as being in the release position;

Fig. 10 is a diagrammatic view similar to Fig. 9 illustrating the automatic braking means in its position fully engaged with the rotary shuttle.

A strand winding machine in which this invention is embodied comprises a rotary shuttle 11 constituting a ring shaped element freely rotatable about its axis. This shuttle is supported between upstanding side frames 12 and 13 and has a peripheral groove (see Fig. 5) into which a supply of wire strand type material is wound. This shuttle is rotated about its axis by a traveling gear ring 14 juxtaposed the shuttle to be supported between the side frames 12 and 13 with their axes coincident. As a matter of convenience the axes are illustrated as on a horizontal line.

Fig. 5 illustrates the side by side positioning of the traveling ring and shuttle. That cross sectional view is taken through a wire guide means (referred to below) attached to the traveling ring and illustrates how the shuttle and ring are supported between the vertically disposed side frames. Both the shuttle and the ring have laterally extending rims 16 and 17, respectively, that are continuous for the full circular length of the respective member of which they are a part. The inside faces of the side frames have continuous circular grooves 18 and 19 into which the laterally extending rims of the adjacent shuttle or traveling ring are disposed with clearance fit. These side frames are clamped together by bolts 21 and have spacers 22 disposed between them to allow for the shuttle and traveling ring to be confined between their inside faces with some clearance between the shuttle, the traveling ring and the side frames.

Suitable means is carried by the traveling ring to guide wire as it unwinds from the shuttle. Preferably, a pulley 26 and a wire guide 27 are carried on the traveling ring, the pulley being rotatably attached thereto by pin 28, and the wire guide being suitably fixed to the traveling ring as by bolt 29.

As can be best seen from Figs. 5 and 6, the wire guide and the pulley are on that side of the traveling ring which is immediately adjacent the inner flat side of the shuttle. And the lip of the guide overhangs the side portion of the shuttle. In order to accommodate the pulley and the wire guide so that they may be carried by the traveling ring, immediately adjacent the shuttle, a portion of the inner side of the traveling ring is removed. Thus, wire drawn from the shuttle is guided over the pulley and between the traveling ring and the shuttle onto the core interlinking the shuttle and traveling ring.

Any suitable driving means may be provided for the traveling ring. In the illustrated embodiment, gear teeth are cut in the peripheral edge portion of the traveling ring. These teeth mesh with a pair of idler gears 31, 32

that are rotated by drive gear 33 of a variable speed drive gear train 34 turned by motor 35. The idler gears are spaced apart a distance predetermined in accordance with a gap in the traveling ring so that one or the other of those idler gears is always engaged with the traveling ring.

In the side frames 12 and 13 there are coincident openings 23 large enough for receiving a ring shaped core 24 onto which the wire carried by the shuttle is wound. A fixed rest is provided for that core and comprises a 10 table surface 25 disposed horizontally and fixed by suitable means (not shown) to the frames.

In addition, as shown in Figs. 2 to 4, suitable, adjustable holding means is attached to the table surface for holding the core. Preferably, this means comprises 15 three similar work holding clamps disposed on the table 120° from each other. Each of these clamps is attached to the table surface at its base by a hand screw 42. Each has an upstanding support 43 with a vertical slot 44 therein from which lateral member 46 extends. This lateral member is movable to be positioned at different levels spaced above the table and carries a roller which is in contact with the upper surface of the core when the machine is ready for operation. The roller is provided with a rubber like surface so as not to cause 25 damage to the wire wound onto the core. Any suitable means, such as hand tool 47, may be provided for rotating the core about its axis as turns of the wire are wound thereon.

In order to interlink or interrelate the core with the shuttle, there is a removable shuttle segment 51 having length about equal to the height of the openings 23 in the side frames. A similar removable segment is not required for the traveling ring which instead may have a gap 52 in its loop corresponding to the approximate height of the openings in the side frames. As mentioned above, however, the length of this gap must be less than the distance between the two idler gears 31 and 32 so that the traveling ring may be constantly driven.

Since the shuttle is normally freely rotatable, a locking means is provided for interconnecting the shuttle with the traveling ring whereby the shuttle may be driven by the traveling ring in a reverse direction to wind a length of wire into the peripheral groove of the shuttle. This locking means preferably is adapted to the removable shuttle segment (Figs. 7 and 8) and constitutes member 53 having an abutment which is disposed to extend laterally of the inner side of the shuttle into the gap of the traveling ring, thereby abutting one end edge of the traveling ring. Screw 54 is carried by the abutment member and is turned into a threaded hole in the side of the shuttle, clamping the abutment member to the shuttle. If desired the abutment member may include a finger like extension 56 which fits into a slot provided in the traveling ring. Of course, where this extension is utilized the length of the abutment member must be less than the length of the gap in the traveling ring so that the shuttle lock means may be easily installed and removed.

In the operation, the shuttle is rotated about its axis as the result of the traveling ring being driven by idler gears 31 and 32. As the pulley and guide of the traveling ring move in their circular path interlinking the core, wire is applied to the core by being drawn from the shuttle. This causes the shuttle to be pulled and to rotate about its axis. The position of the pulley relative to the core is constantly changing during each revolution. Certain of the relative positions of these two elements are illustrated diagrammatically in Figs. 9 and 10. Fig. 9 shows that for approximately one-half of the revolution, the length of wire drawn from the shuttle and extending between the core and the pulley is increasing. Whereas, as shown in Fig. 10, during the approximate other half revolution, the length of wire is decreasing. But since the shuttle is freely rotating, being motivated

by wire being pulled therefrom, and since the aforesaid length of wire drawn from the shuttle is diminishing during approximately the second half revolution of the traveling ring, a problem of slack in the wire develops. 5 The momentum of the rotating shuttle combined with the diminishing required length of wire results in an undesired slack and looping of the wire. In accordance with the teaching of this invention this problem is avoided by automatic means embodied in the winding machine for keeping wire drawn from the shuttle under tension at all times.

Figs. 3, 4, 9 and 10 illustrate a preferred embodiment of this automatic means by which a restraining force is automatically applied to the shuttle during the approximate half revolution of the traveling ring that slack normally would occur in the length of wire between the shuttle and the core.

This means includes a brake shoe 61 which engages a continuous surface of the shuttle and automatic brake shoe actuating means for synchronizing the operation of the brake shoe with rotation of the traveling ring and therefore substantially with the shuttle rotation.

The brake shoe is disposed between the side frames 12 and 13 adjacent the inner peripheral surface of the shuttle. Arm 63 is attached to the brake shoe and projects laterally through side frame 13; rod 64 is attached to arm 63 outside the frame. Two vertically aligned spaced guides 66 and 67 are attached to side frame 13 by suitable means such as welding. Rod 64 extends downwardly through those two guides. The lower portion of this rod is threaded and carries nut 68 which is positioned intermediate the two guides. Spring 69 encircles the rod with its upper end abutting the upper guide and its lower end abutting the nut. The position of this nut on the rod may be adjusted as a means to vary the spring compression. Rod 64 is keyed to cooperate with keyway 71 cut in the lower guide, thereby keeping the rod and the attached brake shoe properly aligned with respect to the shuttle surface against which the brake shoe is applied by the spring, biasing rod 64 to force the brake shoe into engagement with the shuttle surface.

During each revolution of the traveling ring the frictional force exerted by that brake shoe on the shuttle is adjusted in accordance with the tendency of the wire to develop slack. For example, as shown in Fig. 9 when the length of wire between the shuttle and the core should be increasing, the brake shoe may be completely released from engagement with the shuttle, and when the length of wire between the shuttle and the core should be decreasing as shown in Fig. 10, the brake shoe is applied to the shuttle.

The pulley is gear driven at a constant speed; whereas, the speed of the shuttle is varied by action of pulling wire therefrom and by the brake means. It is not necessary to stop or reverse rotation of the shuttle in order to obtain the desired decrease of that length of wire during the second approximately half revolution. Instead, that length of wire is decreased by slowing the shuttle speed without slowing the pulley speed. Since the pulley is gear driven at substantially constant speed, the reduction of speed of the shuttle by the automatic braking action effectively results in the shuttle taking up part of that length of wire. That is, the shuttle, though continuing to move in the direction the pulley is moved, is slowed down and thereby made to have motion in the opposite direction relative to the pulley so that the desired length of the wire is taken up by the shuttle. Then, by automatically releasing the brake during the next half revolution, the shuttle may be pulled at an increasing speed to release the required additional length of wire.

To synchronize the release and application of the brake shoe with the revolution of the traveling ring, rod 64 is reciprocated in response to the rotation of the traveling ring. Means for reciprocating that rod each revolu-

lution of the traveling ring preferably comprises a member oscillated at a frequency corresponding to the speed of revolution of the traveling ring. This oscillating member is lever 72, which pivots at 73 on a pin fixed to the frame of the machine. The oscillation of that lever is effected by cam 74 attached to shaft 75 of gear 76 driven by pinion 77 carried on the shaft of drive gear 33, as can be seen in Fig. 1. The size of these gears is such that the cam rotates one revolution for each revolution of the traveling ring.

In the illustrated embodiment the cam is designed so that during the half revolution represented in Fig. 9, lever 72 is pivoted to act against the spring overcoming the spring action. That is, the lever releases the brake shoe. And during the approximate half revolution represented in Fig. 10, the lever is pivoted so as not to interfere with the spring, whereby the spring is effective to apply the brake shoe to the shuttle. Fig. 3 is a variation of Fig. 10, in which the bolt in lever 72 has been extended so it continues to contact rod 64 when the lever releases the brake, rather than move entirely out of engagement with rod 64 as in Fig. 10.

The brake shoe may be completely released and locked in the released position when desired, as when a supply of wire is being wound into the peripheral groove of the shuttle preparatory to unwinding the wire therefrom onto a core. This release means is manual (seen in Figs. 3 and 4) comprising an arm 78 pivotally connected to post 79 of the frame of the machine. This manually operable arm carries an adjusting screw 81 medially thereon. The adjusting screw normally does not interfere with the oscillation of the lever by the cam. Arm 78 extends through plate 82 which is slotted so that the arm may be moved downwardly and laterally to a position wherein the arm is held by the plate and whereby the arm pivots lever 72 and moves the brake shoe away from the surface of the shuttle. Spring 83 is attached to the arm and to the frame of the machine above the arm to normally hold the arm against the upper end of the slot in plate 82 in which position the arm does not interfere with the automatic action of the cam. Of course, the spring also holds the arm in the offset release position as the spring tensions the arm binding it against the offset portion of the slot in the plate.

Figs. 2, 3 and 4 also show a means for counting the number of turns of the wire that are wound on a core. This counting device 84 is chain driven by sprocket 85 attached to cam shaft 75.

Although but a single embodiment of the present invention has been illustrated and described, it will be apparent to one skilled in the art that various changes and modifications may be made therein without departing from the spirit of the invention or from the scope of the appended claims.

It is claimed and desired to secure by Letters Patent:

1. A machine for winding strand on a ring element, comprising a traveling ring to be interlinked with said element, means for rotating said traveling ring about its axis, a ring shaped shuttle having a peripheral groove for containing a supply of strand to be wound on said element and having a continuous braking surface, a fixed frame for supporting said traveling ring and said shuttle juxtaposed with their axes coincident, strand guiding means carried by said traveling ring through which strand drawn from said shuttle is passed in winding about said element whereby said shuttle is rotated about its axis as said strand is unwound therefrom, and intermittently operable braking means for controlling the speed of said shuttle to tension the strand as it is unwound from said shuttle, said braking means comprising a movable brake shoe disposed adjacent said surface of said shuttle, means for moving said shoe into engagement with said surface of said shuttle, means to periodically act against said moving means to move said shoe out of engagement with said surface of the shuttle to

vary the engagement of said shoe with said surface of said shuttle, and means synchronizing the movement of said periodic means with the rotation of said traveling ring.

2. A machine for winding strand on a core comprising a traveling ring to be interlinked with said core, a ring shaped shuttle having a peripheral groove for containing a supply of strand to be wound on said core and having a continuous braking surface, a frame for supporting said traveling ring and said core juxtaposed with their axes coincident, means for rotating said traveling ring about its axis, strand guiding means carried by said traveling ring through which strand drawn from said shuttle is passed in winding about said core whereby said shuttle is rotated about its axis, and intermittently operable braking means for controlling the speed of said shuttle to tension the strand as it is being unwound from said shuttle, said braking means comprising a movable friction member disposed adjacent said surface of said shuttle, biasing means for moving said friction member into engagement with said surface, cam means rotated in synchronism with the rotation of said traveling ring to act against said biasing means to vary the frictional engagement of said friction member with said surface, and means synchronizing the movement of said cam with the rotation of said traveling ring.

3. A machine for winding strand about a core comprising a traveling ring, a ring shaped shuttle having means for carrying a supply of strand for winding on said core, a frame for supporting said traveling ring and said shuttle juxtaposed with their axes substantially coincident, means carried by said traveling ring to pull strand from said shuttle thereby rotating said shuttle, intermittently operable braking means for controlling the speed of rotation of said shuttle during its rotation to prevent slack of the strand being unwound from said shuttle onto said core, said braking means comprising a movable brake shoe disposed to engage with said shuttle, actuating means attached to said shoe, means cooperating with said frame and said actuating means to bias said shoe to said shuttle to cause the friction between said shoe and said shuttle, means to move said actuating means to vary the frictional engagement of said shoe with said shuttle, and means synchronizing the movement of said moving means with the rotation of said traveling ring.

4. A machine for winding strand about a core comprising a traveling ring, a ring shaped shuttle having a peripheral groove for containing a supply of strand for winding on said core, a frame for supporting said traveling ring and shuttle juxtaposed with their axes substantially coincident, means carried by said traveling ring to pull strand from said shuttle thereby rotating said shuttle, intermittently operable braking means for controlling the speed of rotation of said shuttle to prevent slack of the strand being unwound from said shuttle onto said core, said braking means disposed to engage said shuttle and comprising a movable brake shoe, an actuating rod attached to said shoe, rod guide means attached to said frame, biasing means disposed to act between said frame and said rod to move said shoe with respect to said shuttle to cause friction between said shoe and said shuttle, means to move said rod to vary the frictional engagement of said shoe with said shuttle, and means synchronizing the movement of the rod moving means with the rotation of said traveling ring.

5. A machine for winding strand about a core comprising a traveling ring, a ring shaped shuttle having a peripheral groove for containing a supply of strand for winding on said core, a frame for supporting said traveling ring and shuttle juxtaposed with their axes substantially coincident, means carried by said traveling ring to pull strand from said shuttle thereby rotating said shuttle, intermittently operable braking means for controlling the speed of rotation of said shuttle to prevent

slack of the strand being unwound from said shuttle onto said core, said braking means disposed to engage said shuttle and comprising a movable brake shoe, an actuating rod attached to said shoe, rod guide means attached to said frame, biasing means disposed to act between said frame and said rod to move said shoe with respect to said shuttle to cause friction between said shoe and said shuttle, cam means and a lever, said lever pivotably attached to said frame having one end in contact with said rod whereby movement of said lever results in movement of said rod and having its other end engaged with said cam means, said cam means oscillating said lever about its pivot point to vary the engagement of said shoe with said shuttle, and means synchronizing the movement of the cam means with the rotation of the traveling means.

6. A machine for winding strand on a ring structure, comprising a traveling ring element to be interlinked with said structure, means for rotating said traveling ring element about its axis, a ring shaped shuttle element having a peripheral groove for containing a supply of strand to be wound on said structure and having a continuous braking surface, a frame element supporting said traveling ring element and said shuttle element juxtapositioned with their axes coincident by means comprising a continuous circular projection carried by certain of said elements disposed within and coacting with a continuous circular groove contained by the other of said elements, strand guiding means carried by said traveling ring element through which strand drawn from said shuttle element is passed in winding about said structure whereby said shuttle element is rotated about its axis as said strand is unwound therefrom, and intermittently operable braking means for controlling the speed of said shuttle element to tension the strand as it is unwound from said shuttle element, said braking means comprising a movable brake shoe disposed adjacent said surface of said shuttle element, means for moving said shoe into engagement with said surface of said shuttle element, means to periodically act against said moving means to move said shoe out of engagement with said surface of said shuttle to vary the engagement of said shoe with said shuttle, and means synchronizing the movement of said periodic means with the rotation of said traveling ring.

7. A machine for winding strand on a ring element, comprising a traveling ring to be interlinked with said element, means for rotating said traveling ring about its axis, a ring shaped shuttle having a peripheral groove for containing a supply of strand to be wound on said element and having a continuous braking surface, a frame, the inside faces of said frame having continuous circular grooves, said traveling ring and said shuttle having laterally extending rims, said laterally extending rims disposed within said continuous circular grooves supporting said traveling ring and said shuttle juxtapositioned

5 with their axes coincident, strand guiding means carried by said traveling ring through which strand drawn from said shuttle is passed in winding about said element whereby said shuttle is rotated about its axis as said strand is unwound therefrom, and intermittently operable braking means for controlling the speed of said shuttle to tension the strand as it is unwound from said shuttle, said braking means comprising a movable brake shoe disposed adjacent said surface of said shuttle, means for moving said shoe into engagement with said surface of said shuttle, means to periodically act against said moving means to move said shoe out of engagement with said surface of said shuttle to vary the engagement of said shoe with said shuttle, and means synchronizing the movement of said periodic means with the rotation of said traveling ring.

8. A machine for winding strand on a ring element, comprising a traveling ring to be interlinked with said element, means for rotating said traveling ring about its axis, a ring shaped shuttle having a peripheral groove for containing a supply of strand to be wound on said element and having a continuous braking surface, a frame for supporting said traveling ring and said shuttle juxtapositioned with their axes coincident, strand guiding means 20 carried by said traveling ring through which strand drawn from said shuttle is passed in winding about said element whereby said shuttle is rotated about its axis as said strand is unwound therefrom, locking means for interconnecting said shuttle with said traveling ring whereby 25 said shuttle is driven by said traveling ring in a reverse direction for winding a length of wire onto said shuttle, and intermittently operable braking means for controlling the speed of said shuttle to tension the strand as it is unwound from said shuttle, said braking means comprising 30 a movable brake shoe disposed adjacent said surface of said shuttle, means for moving said shoe into engagement with said surface of said shuttle, means to periodically act against said moving means to move said shoe out of engagement with said surface of the shuttle, 35 means to vary the engagement of said shoe with said shuttle, and means supported by said frame to hold the periodic means against the moving means to retain the shoe out of engagement with said shuttle as the shuttle is rewound.
